UNITED STATES PATENT OFFICE

CHARLES F. KOLB, OF CHICAGO, ILLINOIS

FOLDING BED

Application filed August 17, 1925. Serial No. 50,577.

This invention relates to improvements in folding beds and consists of the matters hereinafter described and more particularly pointed out in the appended claims.

5 One of the objects of the invention is to provide an improved bed construction wherein the bed frame may be readily swung from a normal horizontal position, into an upright position parallel the head frame so that the 10 bed as a whole will occupy but a small space when not in use.

A further object of the invention is to provide an improved counter-balancing mechanism for the bed frame, which will hold the 15 same in any one of a number of angular positions and which mechanism is so arranged that it presents no interference to the bedding and pillows and will not lose its counter-balancing effect through a long and continued 20 use.

Still another object of the invention is to provide a foot end structure of the bow end kind which will automatically fold against the bed frame when the same is being swung upward and which will automatically open into substantially its normal upright position when the bed frame is swung down into its 25 position for use.

A further object of the invention is to 30 provide such a bed wherein the number of parts employed are reduced to a minimum, thus not only reducing the cost thereof but also simplifying its operation and enhancing its appearance.

35 These objects of the invention, together with others, as well as the many advantages thereof will more fully appear as I proceed with my specification.

In the drawings:—

40 Fig. 1 is a view in side elevation of a folding bed embodying my invention, when in its normal horizontal position.

Fig. 2 is a top plan view of the foot end of the bed when in its normal horizontal position.

45 Fig. 3 is a detail view in elevation on an enlarged scale of one of the connections between the bed frame and head frame as viewed from the rear of the head frame.

50 Fig. 4 is a vertical detail sectional view as taken on the line 4—4 of Fig. 3.

Fig. 5 is a horizontal sectional view as taken on the line 5—5 of Fig. 3.

Fig. 6 is a view in side elevation of my improved bed when the bed frame is swung into its vertical or upright position.

55 Fig. 7 is a view in elevation of the head frame, viewed from the rear and when the bed frame is in its normal horizontal position, said view being indicated by the line 7—7 of Fig. 1.

60 Fig. 8 is a view in elevation on an enlarged scale of parts shown at the right hand side of Fig. 7, with several of said parts in a changed relation.

Fig. 9 is a horizontal detail sectional view 65 on an enlarged scale as taken on the line 9—9 of Fig. 8.

Referring now in detail to that embodiment of the invention illustrated in the accompanying drawings: 1 indicates the bed frame 70 upon which the usual mattress and bed clothing is placed, 2 indicates the head frame and 3 indicates the foot frame, which foot frame, in this instance, is of the bow end kind as will later appear. The bed frame 1 includes 75 side members 4—4, a head end member 5 (see Fig. 7) and a foot end member 6, the latter being connected to the side members by the rounded corners, as shown in Fig. 2. Rising from the head end of the bed frame is 80 a supplemental or secondary head frame 7, normally arranged in substantially the plane of the main head frame 2 when the bed frame is in its normal horizontal position. The secondary head frame comprises upright side 85 members 7^a—7^a and a top cross member 7^b, and spaced pickets 7^c may or may not be employed between said top cross member 7^b and the end member 5 of the bed frame.

Braces 7^d connect the secondary head frame 90 with the side members of bed frame as shown in Fig. 1 which braces are so positioned as not to interfere with either the mattress or pillows used upon the bed.

The head frame 2 is in the form of an inverted U shaped member preferably made of rectangular tubing and includes a top cross bar 2^a and upright side bars 2^b—2^b which are spaced a short distance outwardly from the side members of the secondary head frame. 100

The main head frame remains fixed as far as any vertical movement is concerned, but is mounted for a lateral movement upon a support 8 in the form of a door or the like capable 5 of a pivotal movement about a vertical axis as described in my co-pending application, Serial Number 722,663 filed June 27, 1924.

To said support are secured antifriction rollers 9 to receive a channel-like rail 10 fixed 10 to the rear side of the main head frame above the secondary head frame. The bottom ends of the side members 2^b—2^b are connected together by an angle bar 11 which has a thrust bearing against rollers 12 mounted on the 15 bottom of the door 8. As this particular feature forms no part of the present invention it will not be more fully described herein. However, it is not necessary that the head frame be mounted as above described which 20 is by way of illustration only, because the said frame may be fixed with respect to the door. Again if desired a panel 13 may be secured to the rear side of the head frame which panel would then be of a width less 25 than the secondary head frame 7.

To each top corner of the secondary head frame 7 on the rear side thereof is secured a bracket 14 which includes laterally spaced inner and outer ears 15—15 the inner ear including a lateral extension 16. In said ears is located a shaft 17 having a reduced end part 17^a mounted in said extension 16. On the outer end of each shaft is journalled an anti-friction roller 18 which has a body part 18^a 30 adapted for rolling engagement along the rear side of the side of the head frame member 2^b, and a radial flange 18^b arranged between said head frame member and the adjacent ear 15 of the bracket. An expansion 35 coil spring 19 surrounds the reduced end 17^a of the shaft 17 within the lateral extension 16 so as to normally urge said shaft outwardly toward the head frame. As the roller 18 is closed at one end, the spring 19 will always 40 act through the shaft to hold the roller flange against the side member of the head frame. This construction is advantageous because even though said side members of the head frame be out of true or have other inequalities therein, the roller is always held in engagement therewith. On the shaft 16 between the ears 15—15 is journalled a trunnion block 20 which includes a rearwardly extending trunnion 20^a, the purpose of which 45 will appear later.

21 indicates one of a pair of forwardly extending brackets secured near the bottom end of each side member 2^b of the head frame 2. 50 Links 22 are pivoted at one end to said brackets and at their other ends to the side members of the bed frame at a point 22^a forwardly of the secondary head frame 7. Said point may, if desired, be coincident with the point 55 of attachment of the brace link 7^a to the side

members 4 of the bed frame 1 but this is not absolutely necessary, as will be understood.

Means for providing for counter balancing the bed frame in its movement and such means are as follows. Pivotedly connected to each trunnion 20^a is one end of a tension arm 23, the other end of which is pivotally connected to the associated end of a second tension arm 24 by a pin 25. The other end of the last mentioned tension arm is pivotally mounted on a rearwardly extending trunnion 26 of a bracket plate 27 fixed to the rear side of each side member 2^b of the head frame 2, as best shown in Fig. 7, at a point just above the top end of the secondary frame. The associated ends of said tension arms are bifurcated to receive a spiral tension spring 28, one end of which is fixed to the arm 23 and the other of which is fixed to the other tension arm 24, the pivot pin 25 between the two tension arms passing through the open center of the spring.

The foot frame 3, as before mentioned is preferably of the type known as a "bow end" type, wherein the endmost portions of the frame are curved to pass around the rounded corners of the foot end of the bed frame 1, as best shown in Figs. 1 and 2. This brings the end legs of the foot frame into a plane spaced forwardly of the end member of the bed frame and materially enhances the appearance of the bed so as to more nearly simulate a stationary bed of that kind and which is at the present time much in vogue. Said foot frame includes end legs 3^a—3^a spaced rearwardly of the plane of the end member 6 of the bed frame, and intermediate legs 3^b—3^b arranged slightly forwardly of said end member, said leg members being suitably connected together by cross pieces 3^c, panels of any suitable material 3^d being interposed between said legs. On each side member 4 of the bed frame near the end member 6 are upwardly extending brackets 29—29 to which the end legs 3^a are connected by pins providing the pivotal connection 30 (see Figs. 1 and 6) between the bed frame and foot frame, the bottom ends of the legs normally engaging upon the floor when the bed frame is in its normal horizontal position. To the rear side of each intermediate leg 3^b is fixed an angle bracket 31 upon which the end member of the bed frame engages when in its horizontal position. With the pivotal connection or axis arranged as above described, the foot frame will swing in close to the bed frame when the same is swung upwardly into its folded position so as to come within the vertical plane of the head end of the bed as indicated by the dotted line 32 in Fig. 6. Again, this construction permits the top end of the foot frame to position itself below the frame member 6 as best shown in said figure, so that the bed as a whole may be swung through the door opening.

Assume that the bed frame is in its normal horizontal position as shown in full lines in Fig. 1 and it is desired to swing the bed frame into a vertical position for the purpose 5 well known. The operator imparts an upward lift on the foot frame when the rollers 18 will roll down the side members 2^b of the head frame 2 and the links 22 will swing forwardly as the rollers move downwardly. When the bed frame has reached the intermediate position shown by the dotted lines in Fig. 1 the pivotal connection 22^a 10 of the links 22 with the side frame member has reached the limit of its downward swing and the roller 18 has reached a position wherein it is in substantially the same horizontal plane as said pivotal connection. Thus far, the roller has moved a distance greater than that of said pivotal connection 15 22^a and as the roller passes this horizontal plane and continues in its downward movement, said pivotal connection is moving upwardly again until the bed frame reaches its vertical position, the rollers 18 and pivotal connections 22 moving at substantially the same speed and through about the same distance. Thus, in the movement of the bed frame from the horizontal to the vertical movement, the pivotal connection 22^a will swing to its limit 20 25 in one direction and then a part way back again. In the downward movement of the roller, the tension arms 23—24 which are located to the rear of the panel, will open up against the normal contractile tendency 30 of the spiral springs 28 and will counterbalance the weight of the bed frame so that when the bed frame is in its vertical position, said arms will approach parallelism. It is apparent that the above mentioned construction 35 provides a shifting fulcrum connection between the bed frame and head frame.

In this upward movement of the bed frame, the foot frame 3 will swing about its pivotal axis 30 and when said bed frame reaches its vertical position, the foot frame will extend substantially parallel thereto, as best shown in Fig. 6.

In the downward movement of the bed frame 50 the pivotal connection 22^a will first move downwardly and the roller 18 will move upwardly at about the same speed until they reached substantially the same horizontal plane when said pivotal connection 55 will move upwardly, the roller 18 also moving upwardly. As the roller moves upwardly, the tension arms will approach each other and this approach is resisted by the springs carried by said arms which, of course, will 60 prevent the rapid falling of the bed frame under its own weight after leaving said vertical position. During this downward movement of the bed frame, the foot frame will hang in an angular position inclined from 65 the perpendicular, under the action of grav-

ity with the bottom ends of the feet of the foot frame directed toward the head end of the bed. However, as the bed frame approaches its horizontal position, it is only natural for the operator to grasp the top 70 edge portion of the foot frame to bring the bed frame to its horizontal position. During this last part of the movement of the bed frame, the foot frame is, without appreciable effort, swung about its pivotal connection with the bed frame until the brackets on the foot frame engage the foot end of the bed frame when the foot frame is arranged at a right angle to the bed frame. When the bed frame is in its horizontal position, the foot frame rests on the floor in its upright position. The construction of the foot frame is such that it will freely pass the corners of the bed frame and pivoting the foot frame in this manner cuts down 75 80 the combined height of the bed frame and foot frame when the bed frame is in its vertical position. Again this pivotal connection will permit the foot frame to more closely approach the bed frame when the same is 85 90 in its vertical position. In this manner much space both vertically and horizontally is saved, and the saving of space occupied by the bed when not in use, is indeed a matter of importance and is a determining factor 95 in installations.

My improved bed has many advantages. It comprises but a small number of parts which are strong and rigid and may be assembled by unskilled workers without in any manner detracting from the efficient operation of the bed. It is counterbalanced at all times so that there is no possibility of the bed frame swinging downwardly under its own weight to the danger of the operator when bringing the 100 bed frame into its horizontal position. The bed frame cannot bind in its movement because the guides will yield so that the rollers thereof will follow any inequalities in the parts with which they engage. The counterbalancing arms are concealed by the panel on the head frame and which panel also prevents the bed clothes from engagement with said arms.

While in describing my invention, I have 115 referred to certain details of mechanical construction, as well as form and arrangement of parts, the same is for purpose of illustration only so that I do not wish to limit myself thereto except as may be pointed out in 120 the appended claims.

I claim as my invention:

1. A folding bed embodying therein, a head frame including a side member, a bed frame spaced inwardly from said side member, a bracket carried by the bed frame, a shaft mounted in said bracket, and spaced to the rear of the said head frame, a flanged roller on said shaft disposed outside of said side member and engaging one corner there- 125 130

of, and means acting upon said roller to cause the flange to yieldingly engage said corner of said side member.

2. A folding bed embodying therein, a head frame including a side member, a bed frame spaced inwardly from said side member, a bracket carried by the bed frame, a shaft mounted in said bracket and disposed to the rear of said side member for endwise movement toward and away from the side member, a flanged roller on said shaft engaging one corner of said side member and means acting on said shaft to yieldingly move the same endwise toward the side member to hold the roller flange in contact with said corner thereof.

In testimony whereof, I have hereunto set my hand, this 27th day of July, 1925.

CHARLES F. KOLB.
